TELEGRAPH SIGNALING APPARATUS

Albert Henry Masson, Maranhao, Brazil

Application March 29, 1935, Serial No. 13,771
In Great Britain April 10, 1934

13 Claims. (Cl. 178—88)

This invention relates to telegraph signaling apparatus and more particularly to apparatus for the reception of telegraph signals.

In order to overcome interference in telegraphy, and particularly the effects of atmospherics or fading in wireless telegraphy circuits, it is well known to arrange for signals to be repeated from a transmitting station after certain time intervals and for the repeated signals to be superimposed upon the first transmission of the signal so that the original transmission and the repeated signals are compared at a receiving station. The object of the present invention is, in the first instance, to render it unnecessary in such repetition systems to provide more than one repeated signal, although the invention may be applied to obtain improved results with more than one repetition of the signals.

The invention is applicable to the reception of signals transmitted on any code, such as the ordinary cable code or the five-character code but it has special application to the reception of double current cable code signals, that is to say, signals sent by the Morse code in which the signals consist of electrical conditions which are made to persist for various time intervals. The usual practice in double current cable code, an example of which is set out in Patent No. 2,029,-171, filed 15th December 1932, issued Jan. 28, 1936, is to represent a dot by marking current having a duration of 100 per cent of a signaling interval, a dash by spacing current having the same duration and a space by marking current lasting for 50 per cent of a signaling interval followed by spacing current lasting for the remainder of the signaling interval. The present invention enables such signals to be transmitted in one channel and the signals to be repeated after a predetermined time interval in the intervals between the signals of the original transmission which actually form the second channel.

Generally, the system of the present invention presents the following four operating functions: first, when the two successive incoming signals are free from distortion the apparatus records the received signal upon a tape, as by means of a perforation; second, if the second signal is unidentifiable due to fading, etc., the apparatus will record the first and properly received signal; third, the apparatus functions as in the second condition if the first signal is mutilated, but the second signal is undistorted; and fourth, if both the first and second signals are received in a mutilated and an unidentifiable condition, the apparatus will cause the signal recorder to be

obliterated so that the record cannot erroneously show a dot or a dash.

It is known in repetition systems to store the original transmission at the receiving station until the repeated signals arrive so that the original transmission and the repeated transmission can be compared simultaneously. In accordance with the present invention, however, it is necessary to store the second or repeated transmission for a relatively short time because it is desired to allow both the signals of the original transmission and of the repeated transmission to act upon an automatic apparatus which will control the obliterating of the signals and it is necessary to store both transmissions so that this apparatus has an opportunity to act on distorted signals before the latter pass to the receiving apparatus.

The receiving apparatus may consist of an automatic scrutinizing device based on the principle of that set forth in British patent specification No. 286,365 and its effect may be that when mutilated or distorted signals arrive, over the period controlled by the device, it causes impulses of a type generally different from the fundamental signals of the code to be stored on both channels. The storage system may be of any kind such as condenser storage, electromagnetic storage or mechanical storage in which the stored signals are represented by pins or similar movable elements which can be caused to take up one of two or more positions. When condenser storage is employed, the obliterating charges may be charges all of one sign to which all the condensers are charged over the predetermined period. The charges in the condensers on the first transmission channel are stored for a long period before being discharged and those on the second channel for a relatively short period, but when the condensers thus charged are discharged, they render the relays or other receiving apparatus on that particular channel ineffective for the number of signal intervals for which the signals are to be obliterated, so that in each case the other channel takes charge of that time. A device of the kind referred to, sensitive to distortion of the signals, can be employed in dealing with lightning or other brief atmospheric disturbances, but disturbances of longer duration, such as those due to fading, changing of a line or insertion of a wrong plug, may be dealt with by a similar device controlled by failure of the incoming signal current to change over from space to mark. These obliterating devices may be step-by-step devices which, after a predeter-

mined number of steps, cause positive charges to be passed to all the condensers.

Control switches may be provided so that when there are no effective disturbances, the signals 5 are no longer repeated but the two separate channels are available for operating on two separate transmitted messages.

In order that the invention may be clearly understood and readily carried into effect, a telegraph receiver for double current cable code signals arranged in accordance with the invention 10 will now be described more fully with reference to the accompanying drawings, in which:

Fig. 1 is a circuit diagram showing the mode of 15 connection of the receiver.

Fig. 2 is a diagram showing the operation of the device in connection with true and distorted signals.

The signals from the line L are received on a 20 receiving relay RR which functions in the same way as that illustrated in Figures 2, 3 or 4 of the drawings accompanying patent application Serial No. 647,454, now Patent No. 2,029,071, issued Jan. 28, 1936. The upper tongue 1 of this relay deals 25 with the signals on both channels. In the conductors 2, 3 from the mark contact M and the space contact S of this relay, there are contacts 4, 5 which are closed by cams 6, 7 for about 10 per cent of each signal period. These correspond 30 to the charging contacts 46, 47, 48, 49 in Figures 3 and 4 of the drawings accompanying Patent No. 2,029,071. It will be noted that the raised parts of the cam 6 are set at right angles to the raised parts of the cam 7 but both are driven synchronously 35 with the signals in such a way that the contact 4 is closed for receiving dots at a point about three-quarters the way through each signal period as indicated at 6 in Fig. 2, which is more fully described below, and the contact 5 for receiving dashes about a quarter the way through 40 each signal period as indicated at 7 in Fig. 2, and described in the above-mentioned prior patent specification. The dot signals thus picked up are applied to a charging brush c^1 and the dash signals thus picked up are applied to a charging brush c^2 of a rotary distributor switch. This 45 rotary distributor switch is to be operated at the same speed as the transmitting distributor and to be held in synchronism therewith by any of the several well-known methods of correcting 50 from line signals well recognized in the art of telegraphy. The segments of this switch are arranged in two rows or banks, the upper bank $n^1, n^2, n^3 \dots$ being allocated to dot signals and the lower bank $m^1, m^2, m^3 \dots$ being allocated 55 to the dash signals. It will be appreciated that these segments are illustrated as a development of segments set on a rotary drum and the segment n^1 in the upper row appears at both ends 60 just as does the segment m^1 in the lower row: also while sixteen segments are shown in each row, in practice, there will commonly be a considerably larger number of segments to each row. The number of segments is arranged so that 65 when the rotary drum is running at the normal speed for reception, the time between the brush d^1 coming into contact with a particular segment and subsequently the brush g^1 coming into contact with that segment is equal to the time 70 which elapses between the original and repeated transmission of a given part of the signal. This period is chosen as far as possible so that a signal which is lost, or at least badly mutilated during one transmission due to positive static, that is 75 interference, or due to negative static, that is

fading, will not be lost or mutilated during the other transmission. It will also be noted that the segments of the upper row are staggered with respect to those of the lower row, each being spaced exactly half way between two of the segments of the lower row; all of the segments $n^1, n^2, n^3, \dots$ and $m^1, m^2, m^3, \dots$ are each connected to a storage condenser. The dot storage condensers appear at $h^1, h^2, h^3 \dots$; the condenser h^1 is shown duplicated in the drawings for 10 the sake of clearness. Similarly the dash condensers are shown at $k^1, k^2, k^3, \dots$, the condensers being directly connected as shown to their respective segments of the distributor switch and their opposite plates being connected 15 through the conductor 8 to the negative pole of the battery B.

In an alternative arrangement the segments of the distributor switch may be arranged in four 20 banks or rings, the segments of the respective rings being allocated respectively to dot signals on the first channel, dash signals on the first channel, dot signals on the second channel and dash signals on the second channel.

It is clear that either the brushes c^1 and c^2 25 or the segments $n^1, n^2, n^3, \dots$ and $m^1, m^2, m^3 \dots$ can be arranged to rotate but in the particular arrangement illustrated it is assumed that the brushes are rotated and moved from left to right as indicated by the arrow.

It will be noted that in the drawings the segment m^{13} is in contact with the charging brush c^2 and soon a discharging brush comes into contact with that same segment. There is such a discharging brush d^1, d^2 respectively for the dot segments and the dash segments. These brushes, however, are only used for discharging the signal charges belonging to the repeated transmission, and, to insure that the charges stored during the first transmission are not discharged 40 through the brushes d^1 and d^2 , it is arranged that when the segments which have received a current impulse on the first channel reach one of these discharge brushes d^1 and d^2 for the second channel, the conductors from the discharging 45 brushes d^1 and d^2 are interrupted at the contacts 10 and 13 operated by the cams 11 and 14 which are driven at a speed of one revolution in the period of time taken by a brush to pass from the center of one contact such as n^1 to the center of 50 the next but one contact such as n^3 . Thus, the conductor 9 from the brush d^1 is at the requisite instants interrupted at a contact 10 by a synchronously driven cam 11. Similarly, the conductor 12 from the brush d^2 is interrupted at 55 the desired moments by a contact 13 opened by a synchronously driven cam 14. On the other hand, the impulses stored in the condensers through the charging brushes c^1 and c^2 and belonging to the first channel are kept stored in 60 their condensers for almost a complete revolution of the distributor brushes until discharging brushes g^1 and g^2 for the dots and dashes of the first channel arrive on the segments belonging to the first channel. The conductor 15 from the discharging brush g^1 of the first channel includes a contact 16 opened by a synchronously driven cam 17 and in a similar way the conductor 18 from the dash discharging brush g^2 on the first channel includes a contact 19 interrupted 70 by a synchronously driven cam 20. Thus, if any impulses on the second channel remain stored in the condensers when the appropriate segments are in contact with the brushes g^1 and g^2 , the contacts 16 and 19 are then opened and the second 75

channel impulses are prevented from discharging from those brushes. Thus, the time of storage of the dots on the second transmission is represented by the circumferential distance between the brushes c^1 and d^1 , whereas the much longer time of storage of the dots on the first transmission is represented by the circumferential distance between the charging brush c^1 and the discharging brush g^1 , this being equal to the greater part of a revolution of the distributor switch. The difference between these two times of storage is, of course, equal to the delay at the transmitter between the first and second transmission, so that the corresponding signals in a message on both transmissions are discharged simultaneously through the brushes d^1 and g^1 . In a similar way the periods of storage of the dashes on the second and first transmission are represented by the circumferential distance between charging brush c^2 and the discharging brush d^2 and between the brush c^2 and the discharging brush g^2 . The difference between these periods is, of course, the same as for dots.

Generally speaking, in a two channel system with one repetition, it is only necessary to store the signals of the first transmission to bring them into step at the receiver with the second transmission, but in accordance with the present invention, it is necessary to store both transmissions, although the second need be only stored for a relatively short time as explained above. The reason is that both the first and second transmission impulses have to be subjected to the action of the automatic scrutinizing device which will be described below and which must have an opportunity to respond to distorted signals of the second transmission as well as of the first. It will be noticed incidentally that the instants at which the cams 11, 14, 17 and 20 open the contacts 10, 13, 16 and 19 respectively are all the same, but owing to the spacing of the distributor segments $n^1, n^2, n^3 \dots$ and $m^1, m^2, m^3 \dots$, the first transmission is prevented from discharging through the conductors 9 and 12, while the second transmission can and does discharge through those conductors but not through the conductors 15 and 18.

There is a dot and dash relay allocated to each transmission. Thus 21 and 22 are the windings 50 of the dot and dash relays respectively for the first transmission and 23 and 24 the windings of the dot and dash relay of the second or repeated transmission. It has already been explained that the signal impulses which correspond in the first and second transmissions affect the relay windings 21 or 22 and 23 or 24 at the same moments through the conductors 15, 25 or 18, 26 and 9, 27 or 12, 28.

Thus, when a dot is received, it will, through 60 the charging brush c^1 , charge two of the dot condensers at times separated by a period of delay, but after impulses on the two channels have received their respective storage times they will discharge simultaneously through the two dot discharging brushes d^1 and g^1 . All the condensers are given positive charges because the main tongue 1 of the receiving relay RR is connected direct to the positive pole of the battery B which is therefore connected to the storage condensers 65 in the proper circumstances through one of the contacts M, S of the relay RR and through the contacts 4 or 5 and the brushes c^1 or c^2 , the opposite plates of the condensers, as already mentioned, being connected directly to the negative 70 pole of the battery B. The opposite sides of the

windings 21, 22, 23, 24 are also connected direct to the negative pole of the battery B so that when a dash is received, as described above, the discharge of the respective storage condensers on the two channels through the discharging 5 brushes g^1 and d^1 respectively will cause energization of the relay windings 21 and 23. Similarly, if a dash is received without distortion, the relay windings 22 and 24 are energized by the discharge of the dash condensers through the 10 brushes g^2 and d^2 respectively. In addition to the windings 21, 22, 23 and 24, the four relays are furnished with locking windings 29, 30, 31 and 32 with locking contacts 33, 34, 35 and 36 to which these locking windings are directly connected. The windings 31 and 32 are connected through safety resistances r^1, r^2 and a contact 37 to the positive pole of the battery B, and similarly, the opposite sides of the locking windings 29 and 30 are connected through safety resistances 20 r^3 and r^4 and a contact 38 to the negative pole of the battery B. Consequently, when any one of the relay windings 21, 22, 23 or 24 is energized, the tongues 39, 40, 41, 42 of these relays remain held up until the locking circuit of the relay is 25 interrupted by the cam 43 in the case of the first transmission and the cam 44 in the case of the second transmission. These cams 43, 44 are synchronously driven exactly as described with reference to Figures 3 and 4 of the drawings accompanying Patent No. 2,029,071. Thus, when a relay is momentarily energized by a condenser discharge, it is maintained energized for a substantially longer period by the current passing through the contacts 37 or 38, but it is released 30 by those contacts opening before it is to be energized by the following condenser discharge. Now the tongues 39 and 40 of the dot relay 21 and dash relay 22 on the first transmission are connected together and are connected to the positive pole of the battery B. The main contacts 45 and 46 of these relays are each connected through a change over switch 47 to the respective windings 48, 49 of a centrally biased differential relay, the tongue 50 of which is shown in the central position to which it returns. The other sides of the windings 48, 49 are respectively connected to the main contacts 51, 52 of the dot and dash relays 23, 24 belonging to the second or repeated transmission. The tongues 41, 42 of 40 these relays are also connected together but in this case are connected to the opposite pole of the battery B, that is the negative pole. 45

In order to aid in the further understanding of the invention, reference should be made to the 55 diagram shown in Fig. 2 of the drawings. In this diagram the vertical lines $t^1, t^2, t^3 \dots t^{11}$ represent the divisions between signal periods. The first heavy line extending across the diagram represents the position of the arm 1, the upper 60 portions M of this line indicating the position of the lever 1 in contact with the marking contact M, while the sections S represent times when the lever 1 is in contact with the spacing contact S. In the period t^1, t^2 the arm is on contact M during 65 the first half of the period and on contact S during the second half. In the period t^2, t^3 the arm remains on contact M, while in the period t^3, t^4 the arm remains on contact S. The next cross line represents by the sections 6 the periods 70 in which the cam 6 closes the circuit at 4, while the next line represents by the sections 7 the periods in which the cam 7 closes the circuit at 5. The first line corresponds therefore to marking 75 and the second to spacing. It will be evident that 75

during the period t^1, t^2 the arm 1 is on contact S when cam 6 closes contact 4. Therefore no circuit will be closed, and this condition represents a space. In the period t^2, t^3 however the cam 5 6 closes the contact 4 during the second half period when arm 1 is on contact M, and thus charges the condensers h through brush c¹. In the same way during the period t^3, t^4 cam 7 closes contact 5 during the first half period when 10 arm 1 is on contact S, thus completing a circuit to brush c² and charging condensers k.

The signals shown to the left of the line x—x in Fig. 2 are true or undistorted signals since 15 each segment begins and ends exactly on the line between signaling periods. At the right of the line x—x the signals are represented as distorted, or in other words as terminating or starting before or after the division line between signaling periods. Along the line B the arrows 20 indicate the change in position of the arm 1, the downward arrows indicating a shift from M to S and the upper arrows a shift from S to M. It will be noted that with true signals these arrows fall at the end of some half period. To the right 25 of the line x—x however, since these changes of position do not occur at the exact end of a signaling period, the arrows are out of line with the half periods.

The line C represents the action of the cam 30 114. During the lower sections 116 of the line, arm 115 is in contact with lever 116 and current can flow from condenser 112 through resistance 113 to the positive pole of the battery. On the other hand, the lines 117 represent the periods in 35 which arm 115 engages contact 117, so that if any current flows during this period it must pass through the coil 63.

During normal operation with true signals, it 40 is evident that the arrows B are always opposite the sections 116 of the curve C. Or in other words at the period of changing from M to S a circuit is always open through resistance 113 and not through coil 63. On the other hand, the arrows to the right of the line x—x are at times 45 opposite the sections 117 of the curve 116, as for example the arrows b¹, b² and b³, also indicated by arrows d¹, d² and d³. Therefore when the signals become distorted some of the changes in position of lever 1 will take place at such times 50 as to cause current to flow through the coil 63 and operate the mechanism herein described.

The operation of the mechanism will be described in further detail herebelow.

If normally formed signals, that is signals 55 without more than a certain degree of mutilation, are being received the operation is as follows: When a dot is received the relay windings 21 and 23 are energized as already described and these 60 relays pull up and are locked for the period determined by the cams 43 and 44. The result of this is that there is a circuit from the positive pole of battery B through the conductor 53, through the tongue 39 of the dot relay on the first channel, contact 45, change over switch 47, differential relay winding 48, contact 51 and tongue 41 of the dot relay on the second channel through conductors 54 and 8 to the negative pole of battery B. Thus, the dot winding 48 of the differential relay is energized and the tongue 50 70 drawn over against its dot contact 55. The result is that the positive of the battery B, which is connected through conductor 56 to the tongue 50 of the differential relay, is connected to conductors 57 and 58 of the main re-perforator MP and the spare re-perforator SP respectively, the

contact 59 of the change over switch 47 being closed. The mid-points of the windings of the perforators MP and SP are shown connected to the negative of the battery B in the usual way so that one half of the winding of each is energized 5 to punch a dot in the paper strip.

If a dash is received, a similar circuit is completed, from the positive of the battery B, through the conductor 53, tongue 40 and contact 46 of the dash relay on the first transmission, 10 through change over switch 47 and the dash winding 49 of the differential relay, contact 52 and tongue 42 of the dash relay on the second transmission and through conductors 54 and 8 to the negative pole of the battery B. The tongue 15 53 is therefore now drawn over to the right against its dash contact 50 so that the tongue 50 connects the positive of the battery B to the conductors 61 and 62 respectively of the re-perforators MP and SP, with the result that the 20 opposite halves of their windings are energized and a dash is punched in the perforated strip.

When no signals are received, the tongue 50 of the differential relay remains in the central position illustrated. If, however, owing to a 25 fault, the dot and dash relay windings 21, 22, 23, 24 are all energized at the same time, then the differential relay is balanced and the tongue 50 remains in its central position so that no perforating takes place. It is, however, an advantage to leave blanks in the tape when a fault of this character occurs as it makes it possible for the operator to fill in the correct holes in the paper tape. Also in addition, undistorted signals which differ in the two receptions will also 35 cause the occurrence of blanks and it may be arranged that upon the occurrence of either of these conditions, the operator may be notified by an audible or visual signal, although the circuits of such a signal are not shown in the drawings. 40

In order to deal with the reception of mutilated signals, in such a case it is arranged that the mutilated signals on one transmission may be obliterated so as to leave the apparatus to be controlled by the signals of the other transmission. 45 For this purpose an automatic scrutinizing device is employed arranged on the lines described in British patent specification No. 286,365. In that specification, if the signals are mutilated beyond a certain extent, the condenser K is arranged to discharge through an alarm device A shown in Figure 1 of the drawings accompanying that specification. In the present case, however, an electromagnet with its winding 63 is provided in the place of the alarm device A. Each time an additional tongue 96 of the receiving relay RR moves over, a condenser 112 is charged or discharged through a resistance 113 or through the winding 63. A cam 114 is driven to make one revolution during the time of two aggregate 60 centre holes, that is, two centre holes of the combined channel signals as received. Since the apparatus is organized to handle double-current cable-code signals, when the signals are undistorted, the tongue 96 moves over only at the beginning or half-way through each aggregate 65 centre-hole period. The cam 114 is arranged and timed so that during these normal times of change-over of the tongue 96, the arm 115 rests against its contact 116, with the result that the 70 condenser 112 then charges and discharges through the resistance 113. If, however, the tongue 96 of the receiving relay RR moves over during the times that cam 6 or cam 7 is closing its contact 4 or 5 respectively—or closely before 75

or after those times, since the lifts of the cam 114 are usually designed to provide some margin—the cam 114 has pressed the arm 115 over against the contact 117 and the condenser 112 charges or discharges through the winding 63. The winding 63 may, however, be arranged under the control of a relay to be energized on the occurrence of signals of an amplitude in excess of a predetermined value, such as for example, might occur due to lightning or it might be responsive both to excess amplitude and a predetermined degree of distortion. This device is arranged to work in co-ordination with a pair of obliterating brushes o^1 , o^2 , with which the rotary distributor 15 is provided. The winding 63 controls an armature 64 arranged when the winding 63 is energized to retract the check pawl 65 of a ratchet wheel 66. This ratchet wheel 66 is stepped round one tooth at each signal interval by a driving pawl 67 which is rocked by a synchronously driven cam 68 in step with the signals. On the spindle 69 of the ratchet wheel 66 there is a cam 70 with a raised portion 71 and when the check pawl 65 is retracted by the winding 63, the ratchet wheel 66 and the cam 70 are turned by a spring 72 in the clockwise direction until the raised part 71 of the cam 70 comes against a stop 73. When normal undistorted signals arrive, however, the winding 63 is not energized and consequently the ratchet wheel 66 is turned one step counter-clockwise at each signal interval until a point is reached when the raised portion 71 of the cam 70 comes into contact with a spring blade 74 and separates it from a contact 75 and at the same time acting through an insulating distance piece 76 it separates a further spring blade 77 from a contact 78; that is the normal state of the apparatus when ordinary undistorted signals are being received.

The dot obliterating brush o^1 is connected through a contact 79 controlled by a synchronously driven cam 80 to the contact 75 while the contact springs 74 and 77 are connected by conductors 81 and 53 to the positive pole of battery B. Similarly, the dash obliterating brush o^2 is connected to a contact 82 also controlled by the cam 80 and thence to the contact 78. The cam 80 as well as the other cams 6, 7, 11, 14, 17, 20, 43, 44, 68 and 114 are all driven synchronously and held in synchronism with the transmitting apparatus in the same way as the receiver rotary distributing switch. All of these cams are operated so as to make one revolution during each channel centre-hole period, that is, during every two centre-hole periods of the combined channel signals as received.

Now if suddenly some mutilated signals arrive and cause the winding 63 to be energized, the latter retracts the check pawl 65 which may remain retracted by the action of a locking winding 83, which will be referred to below, until the line receiving relay RR changes position. Therefore the spring 72 rotates the ratchet wheel 66 and the cam 70 into the zero position shown in the drawings against the stop 73 so that the contacts 74, 75 on the one hand and the contacts 77, 78 on the other hand immediately close. Therefore at each signal interval the contacts 79 and 82 are closed and through them and the contacts 74, 75 and 77, 78 the positive pole of battery B is connected to the two obliterating brushes o^1 , o^2 . Therefore both the dot and dash condensers on both channels are all positively charged until the two pairs of spring contacts 74, 75 and 77, 78 are opened again. When the mutilation ceases, the

pawl 67 again turns the ratchet wheel 66 step-by-step and it may be arranged that it has to turn through a distance of three teeth before the contacts 74, 75 and 77, 78 are separated so that the obliterating charges are cut off at a time of three signal intervals after the distorted signals cease.

The effect of the obliterating charges when the first transmitted signal in the first channel is clear, and the second transmitted signal in the second channel is mutilated, may be briefly explained as follows: The obliterating charges belonging to the second channel will be discharged through the brushes d^1 , d^2 after a short period of storage. When they are discharged they will result in the dot and dash relays 23 and 24 on the second channel being held up for the whole time during which the obliterating condensers are being discharged on the second channel. During that time, however, condensers are being discharged at the discharge brushes g^1 and g^2 on the first channel, but these condensers are not charged with obliterating charges at all as owing to the long period of storage on the first channel, those condensers received the first transmission before the disturbance giving rise to distortion occurred, and they received that part of the signal corresponding to the part of the repeated transmission which was obliterated; therefore, they cause the dot and dash relays 21 and 22 belonging to the first channel to be actuated in accordance with that part of the signal. It will be appreciated from the detailed circuits described above that the relays 21 and 22 then take full control because the circuits of the windings 48 and 49 of the differential relay cannot be completed by the relays 23 and 24 alone, but the circuits are only completed respectively when either the relay 21 or 22 is energized.

On the other hand, when the first signal is mutilated and the second signal is clear, the obliterating charges on the first channel are stored for a relatively long time and when they arrive at their discharging brushes g^1 , g^2 , the relays 21 and 22 on the first channel will be continuously held attracted while the obliterating condensers are discharged on the first channel. However, owing to that long period of storage on the first channel, the obliterating charges on the second channel have already been discharged and at the time in question, under normal conditions, signals without distortion are arriving at the discharge brushes d^1 , d^2 on the second channel which were transmitted after the disturbance causing distortion had ceased, but which, nevertheless, owing to the time delay, correspond with the obliterated signals on the first channel. In this case, therefore, the dot and dash relays 23, 24 on the second channel take charge entirely and control the energizing of either the dot or dash windings 48, 49 of the differential relay.

In order to deal with failures such as those due to fading, changing the line, or the insertion of a wrong plug, a further device is provided generally similar in construction to that just described. This device, which is generally of the nature of a device for counting the reversals of the receiving relay RR, is only capable of dealing with such faults if they have a relatively short duration. Generally, the receiving relay RR operates tongue 96 to energize relay 101 so that movement of the ratchet wheel 84, and the cam 87, controls the periods when obliterating charges are passed to the brushes o^1 and o^2 . The device has a ratchet wheel 84 generally similar to the wheel 66 and advanced one tooth at each signal

period by a pawl 85 driven like the pawl 67 from the cam 68. It also has a spring 86 tending to turn the ratchet wheel in a clockwise direction. The ratchet wheel drives a cam 87 with a raised portion 88 which is turned against a stop 89 when the check pawl 90 is drawn away from the wheel 84. There are two pairs of contacts in this case also under the control of the cam 87, also consisting in each case of a spring blade and contact 91, 92 and 93, 94, but in this case, when the cam is in the zero position against the stop 89, these contacts are open as shown in the drawings so that then no obliterating impulses pass to the obliterating brushes c^1, c^2 . As before the springs 91 and 93 are connected to the positive pole of the battery B for which purpose the conductor 95 is provided and the contacts 92 and 94 are connected respectively to the obliterating brushes through the contacts 82 and 79.

20 To provide for the control of this device, the main receiving relay RR is provided with an additional tongue 96 and an additional pair of contacts 97, 98 controlled by the tongue and connected respectively to the positive and negative sides of the battery B through conductors 95 and 99. The tongue 96 is connected directly to a condenser 100, the other side of which is connected to a winding 101 of an electromagnet which when energized withdraws the check pawl 90. The winding 101 is connected through a resistance 102 to the positive pole of battery B. Thus, when the tongue 96 moves over to the contact 98, as shown in the drawings, there is a charging circuit for the condenser 100 through the winding 101 from the battery B and when subsequently the tongue 96 moves over to the spacing contact 97, the condenser 100 is able to discharge itself through the winding 101 and resistance 102. Thus, every time the relay RR crosses over from its space to its mark contact or vice versa a current impulse passes through the winding 101 and each time the winding 101 retracts the check pawl 90 so at each cross-over of the relay RR, the ratchet wheel 84 is released and the cam 87 brought 45 against the stop 89. If, however, the relay RR fails to cross over for a number of signal periods, the check pawl 90 is not withdrawn and the driving pawl 85 turns the ratchet wheel 84 step-by-step through the amount of one tooth at each 50 signal period. After a predetermined number of periods which, in the example shown, is arranged to be twelve signal periods, the raised portion 88 of the cam 87 closes the contacts 91 and 92 and the contacts 93 and 94 so that, as already described in connection with the automatic scrutinizing device, obliterating impulses are sent from the positive pole of the battery through conductors 95, 103 and the two pairs of contact springs and contacts 79 and 82 to both obliterating brushes and this continues until the receiving relay RR changes over to cause the check pawl 90 to release the wheel 84, whereupon the cam 87 is turned back by the spring 86 to the position shown and the contacts 91, 92 and 93, 94 are 65 opened again.

It has already been indicated that when the check pawl 65 is drawn down it can be locked down by the winding 83 until the main receiving relay RR changes over. For this purpose the winding 83 is connected across the battery B through a pair of front contacts 104 controlled by its own armature 64 and through a pair of back contacts 105 controlled by the armature of the winding 101. Thus, when the armature 65 is drawn down by the scrutinizing winding 63 the

circuit through the winding 83 is completed to hold down the check pawl 65 until the relay RR reverses its position when the pawl 90 is drawn down and the contacts 105 opened.

The re-perforators MP and SP have their circuits controlled by switch blades 59 and 106 which connect the re-perforators as already described when they are closed at their upper contacts 107. They can be turned down, however, on to their lower contacts 108 when the switch 47 is turned from its upper contacts 109 to its lower contacts 110. When both switches are in the upper position, the connections are as already described. When they are in the lower position, however, the connections are altered in the following way: 15 First of all the switch 47 connects the positive pole of battery B through the conductor 56 and the conductor 111 direct to the windings 48 and 49 of the differential relay so that this relay is only under the control of the relay tongues 41 and 42. The contacts 45 and 46 and the tongues 39 and 40 are now removed from the circuits of the windings 48 and 49 by the switch 47. Secondly, the tongue 50 of the differential relay through its contacts 55 and 60 can only connect 25 with the windings of the re-perforator MP. The windings of the re-perforator SP on the other hand, are connected by the switch blades 59 and 106 though the contacts 108 to the contacts 45 and 46 of the relays 21 and 22 and thence through 30 the tongues 39 and 40 to the positive pole of the battery B. Thus the signal received on the first transmission is perforated by the re-perforator SP and that received on the second transmission by the re-perforator MP. 35

It has already been indicated that the invention is applicable to codes other than the double current cable code. When the invention is applied to ordinary cable code, for example, the relay 4 in the drawings is replaced by a relay, the tongue 40 of which is biased to the central position but is drawn over to the left or right respectively by incoming dot or dash signals. In that case, the cams 6 and 7 instead of being arranged to operate the contacts 4 and 5 alternately as in the 45 drawings, are set to operate the contacts simultaneously and are phased or timed so that the contacts 4 and 5 are closed at the middle of each period of contact of the relay tongue 4 due to the incoming dot and dash signals. In that case 50 also the charging brushes c^1, c^2 are so placed that they are in contact with a segment during the time that the contacts 4 and 5 are closed. They would, therefore, be staggered just as the other pairs of brushes are staggered in the drawings, 55 or in other words, in the position illustrated, the brush c^1 would be making contact with the segment n^{14} .

Again for a receiver to operate on five-unit code, the relay 4 is as shown in the drawings 60 so that its tongue will be in contact with the marking contact M or the spacing contact S during the time of each of the signal units which go to make a character, this depending upon the combination of such mark and space units forming each character. The cams 6 and 7, in that case, are arranged to cause both contacts 4 and 5 to close at the middle of every such signal unit period and the brushes c^1, c^2 are placed so as to be each in contact with a segment during the 70 times the contacts 4 and 5 are closed. That is to say, in the position shown, the brush c^1 would be in contact with the segment n^{14} just as for ordinary cable code.

In the case of five-unit code, however, the relay 75

50 need not be a centrally biassed relay, but may be a neutral relay drawn to one side or the other by the marking or spacing signals respectively and remaining in the position in which it is last placed until displaced by a further signal element. The re-perforators MP and SP are replaced by apparatus for transcribing the five-unit signals. Generally a five-unit synchronous system is operated as a multiplex system with the 5
10 five-unit characters allocated in sequence to a number of channels. In such a system, the re-perforators MP and SP would be replaced by synchronous apparatus for separating the channels and by the several printers allocated respectively 15 to each channel; such synchronous apparatus and printers are, of course, well known in themselves.

It has already been indicated also that the invention is applicable to receivers with other 20 forms of storage than the condenser storage illustrated in the drawings. When the invention is applied to a receiver employing mechanical storage, sets of movable members such as pins are employed for dots and dashes generally as set 25 forth, for example, in British patent specification No. 111,343. These movable members may be arranged alternately on one drum, or at different axial positions on the drum. When the signals are repeated once so that the original transmission 30 and the repeated transmission are in effect sent on two channels, alternate dot pins are allocated to the original transmission and to the delayed transmission and, similarly, alternate dash pins are allocated to the original transmission 35 and to the delayed transmission. At one point in each revolution of the drum, all the pins are reset by a plough or similar cam device into the initial position and on arriving at the actuating point, if a dot signal is received one of the dot 40 pins is displaced, and if a dash signal is received one of the dash pins is displaced. According to the present invention, during a period when the signals are distorted or mutilated beyond a predetermined degree, the whole of the dot pins and 45 the whole of the dash pins are actuated and therefore set over into the signal position. Each set of pins, both the dot pins and dash pins, co-operate with a pair of levers which correspond to the dot discharge brushes d^1, g^1 and d^2, g^2 on 50 the two channels respectively. Each pin which is actuated or set in the signal position acts upon both levers when it arrives at the appropriate positions and causes each lever to make a contact corresponding to those made by the discharge 55 brushes in the drawings. The contacts are connected to conductors in which there are cam-closed contacts such as shown in the drawings at 10, 13, 16, 19, the purpose being exactly the same as in the system illustrated, that is to say, to 60 ensure that the circuits through the relay windings 21, 22, 23 and 24 shall only be completed by the appropriate dot or dash pins. In other respects, the system is similar to that illustrated in the drawings.

65 I claim:—

1. A telegraph receiving system for cable code signals, comprising in combination, a signal receiving relay for receiving an original and a repeated transmission of signals, a signal impulse 70 storage device comprising a bank of condensers for storing the dot signals of both of said transmissions, a bank of condensers for storing the dash signals of both of said transmissions, synchronously actuated switching means connected 75 to said receiving relay for charging said dot and

dash storing condensers and synchronously actuated switching means for discharging said dot and dash storing condensers after different time intervals for said two channels to bring the dot and dash signals of both channels into step, a receiving apparatus comprising separate elements connected respectively to said switching means for discharging said dot storing condensers and to said switching means for discharging said dash storing condensers and means responsive to a predetermined degree of distortion in the received signals comprising synchronously actuated switching means connected to apply charging impulses to said dot and dash storing condensers so as to obliterate the signals of both of said transmissions received during the period of signal distortion. 5

- condensers of said two banks after different periods to bring the corresponding signals of both of said transmissions into step, a receiving apparatus comprising separate elements connected 5 respectively to said switching means for discharging said dot storing condensers and to said switching means for discharging said dash storing condensers, and means responsive to a predetermined degree of distortion in the received 10 signals for passing from said battery to said banks of condensers, impulses of like polarity to the stored signal impulses so as to obliterate the stored signals received during the period of signal distortion.
- 15 4. A telegraph receiving system for cable code signals, comprising in combination, a signal receiving relay having spacing and marking contacts for receiving an original and a repeated transmission of signals, a bank of condensers for 20 storing the dot signals of both of said transmissions, a second bank of condensers for storing the dash signals of both of said transmissions, a local battery connected to the tongue of said signal receiving relay, synchronously actuated 25 switching means for connecting the marking contact of said signal receiving relay to each of said first-mentioned bank of condensers in sequence so as to charge one of said condensers from said battery upon the reception of each dot signal, 30 further synchronously actuated switching means for connecting the spacing contact of said signal receiving relay to each of said second-mentioned bank of condensers in sequence so as to charge one of said condensers from said battery 35 upon the reception of each dash signal, synchronously actuated discharging means for discharging the condensers of said two banks after different time intervals to bring the corresponding signals of both of said transmissions into step, a receiving apparatus comprising separate elements 40 connected respectively to said switching means for discharging said dot storing condensers and to said switching means for discharging said dash storing condensers, further synchronously actuated switching means organized to make connection with said condensers in sequence, connections from said last-mentioned switching means to said battery and contacts included in 45 said connections and operable upon the occurrence of a predetermined degree of distortion in the received signals to connect said battery to said last-mentioned switching means.
5. A telegraph receiving system for cable code signals, comprising in combination, a signal receiving relay having spacing and marking contacts for receiving an original transmission and a repeated transmission of the same signals, a bank of condensers for storing the dot signals of both of said transmissions, a second bank of 55 condensers for storing the dash signals of both of said transmissions, a local battery connected to the tongue of said signal receiving relay, synchronously actuated switching means for connecting the marking contact of said signal receiving relay to each of said first-mentioned bank of condensers in sequence so as to charge one of said condensers from said battery upon the reception of each dot signal, further synchronously actuated switching means for connecting the spacing contact of said signal receiving relay to each of said second-mentioned bank of condensers in sequence so as to charge one of said condensers from said battery 60 upon the reception of each dash signal, synchronously actuated discharging means for discharging the condensers of said two banks after different time intervals to bring the corresponding signals of both channels into step, a receiving apparatus comprising separate elements connected respectively to said means for discharging said dot storing condensers and to said means for discharging said dash storing condensers, further synchronously actuated switching means organized to make connection with said condensers in sequence, connections from said last-mentioned switching means to said battery, contacts included in said connections, a contact closing device driven in step-by-step fashion in synchronism with the received signals and operatively connected to close said contacts after a definite number of signal periods and an electromagnet energized upon each change-over of said signal receiving relay to declutch said mechanism so as to cause said contacts to separate.
7. A telegraph receiving system for double current cable code signals of the type set forth, comprising in combination, a signal receiving relay for receiving a transmission of signals on one 65 channel and a transmission of the same signals repeated after a predetermined time delay on another channel, a signal impulse storage device comprising a set of storage elements for storing the dot signals of both of said transmissions and a set of storage elements for storing the dash signals of both of said transmissions, synchronously actuated switching means for conveying impulses to the storage elements of said respective sets upon the arrival of dot or dash signals, a receiv- 70 75

ing apparatus connected to said signal impulse storage device to be actuated simultaneously by corresponding signals of both of said transmissions and means responsive to a predetermined degree of distortion in the received signals for rendering said receiving apparatus insensitive to signals of both of said channels received during the period of signal distortion.

8. A telegraph receiving system for double current cable code signals of the type set forth, comprising in combination, a signal receiving relay for receiving an original transmission and a transmission of the same signals repeated with a predetermined time delay, a signal impulse storage device comprising a bank of condensers for storing the dot signals of both of said transmissions, a bank of condensers for storing the dash signals of both of said transmissions, synchronously actuated switching means for applying charging impulses to the condensers of said respective banks upon the arrival of dot or dash signals and synchronously actuated switching means for discharging said dot and dash storing condensers after different time intervals for said two transmissions to bring the dot and dash signals of both transmissions into step, a receiving apparatus comprising separate elements connected respectively to said switching means for discharging said dot storing condensers and to said switching means for discharging said dash storing condensers and means responsive to a predetermined degree of distortion in the received signals comprising synchronously actuated switching means connected to apply charging impulses to said dot and dash storing condensers so as to obliterate the signals of both of said transmissions received during the period of signal distortion.

9. A telegraph receiving system for cable code signals, comprising in combination, a signal receiving relay for receiving an original transmission and a transmission of the same signals repeated with a predetermined time delay, a bank of condensers for storing the dot signals of both of said transmissions, a second bank of condensers for storing the dash signals of both of said transmissions, synchronously actuated switching means connected to said receiving relay for charging said dot and dash storing condensers, synchronously actuated switching means for discharging said dot storing condensers and for discharging said dash storing condensers, said discharging means being so timed that stored signal impulses corresponding to the same signal elements in the original and repeated transmissions are discharged simultaneously, a receiving apparatus comprising a dot relay and a dash relay allocated to the original transmission with a dot relay and a dash relay allocated to the repeated transmission, connections between said relays and said discharging means for energizing the respective relays upon the discharge of corresponding stored signal impulses, connections for connecting in series the contacts of said two dot relays, connections for connecting in series the contacts of said two dash relays, a differential relay having opposed windings connected respectively in circuit with the contacts of said two dot relays and in circuit with the contacts of said two dash relays, a pair of receiving instruments actuated under the control of the opposite contacts of said differential relay and means responsive to a predetermined degree of distortion in the received signals for causing certain of said condensers to be charged to prevent the selective

operation of said receiving instruments due to the signals received during the period of signal distortion.

10. A telegraph receiving system for double current cable code signals, comprising in combination, a signal receiving relay for receiving an original transmission and a transmission of the same signals repeated with a predetermined time delay, a synchronously operated contact-making device connected to the marking contact and a second synchronously operated contact making device connected to the spacing contact of said receiving relay, a synchronously driven rotary distributor switch comprising a ring of contact segments allocated to dot signals, a second ring of contact segments allocated to dash signals, a dot charging brush co-operating with said first-mentioned ring of contact segments and connected to said first-mentioned contact-making device, a charging brush co-operating with said second-mentioned ring of contact segments and connected to said second-mentioned contact-making device, a bank of storage condensers respectively connected to the contact segments of said first-mentioned ring, a second bank of storage condensers respectively connected to the contact segments of said second-mentioned ring, a pair of dot discharging brushes co-operating with said first-mentioned ring of contact segments and a pair of dash discharging brushes co-operating with said second-mentioned ring of contact segments, connections from said discharging brushes and synchronously driven contact-making devices in said last-mentioned connections and timed so that the dot impulses derived from the original transmission are discharged through one of said dot discharging brushes and the dot impulses derived from the second transmission are discharged through the other of said dot discharging brushes, while the dash impulses derived from the first transmission are discharged through one of said dash discharging brushes and the dash impulses derived from the second transmission are discharged through the other of said dash discharging brushes, the discharging brushes being so spaced that stored signal impulses corresponding to the same signal elements in the original and repeated transmissions are discharged simultaneously, a receiving apparatus, comprising dot relays allocated respectively to the original and repeated transmissions, dash relays allocated respectively to the original and repeated transmissions, connections between said relays and said discharging brushes for energizing the respective relays upon the discharge of the corresponding stored signal impulses derived from the two transmissions, connections for connecting in series the contacts of said two dot relays, connections for connecting in series the contacts of said two dash relays, a differential relay having opposed windings connected respectively in circuit with the contacts of said two dot relays and in circuit with the contacts of said two dash relays, a pair of receiving instruments actuated under the control of opposite contacts of said differential relay, a local battery connected, on the one hand, to the tongue of said signal receiving relay and, on the other hand, to each of said storage condensers, a pair of obliterating brushes each co-operating with one of said rings of contact segments, and means responsive to a predetermined degree of distortion in the received signals for connecting, during the period of signal distortion, said obliterating brushes to the pole of said battery which is con-

nected to the tongue of said signal receiving relay.

11. A telegraph receiving system for receiving one transmission of signals and a single subsequent repetition of the same signals, comprising in combination, a signal receiving relay, a signal impulse storage device operatively connected to said receiving relay and organized to store the signal impulses of the original transmission and 10 the repetition in separate storage elements and for different periods to bring the corresponding signals of the original transmission and of the repetition into step, means responsive to a pre-determined degree of distortion in either of the 15 received signals and operative upon said signal storage device to destroy the identity of signal impulses stored therein and a receiving apparatus connected to receive simultaneously the stored signal impulses representing a signal of the original 20 transmission and the same signal of the repetition and comprising a pair of relay devices controlled respectively by the stored signal impulses of the original transmission and of the repetition and a receiving or recording circuit 25 connected to be controlled solely by one of said relay devices at times only when the identity of the stored signal impulses controlling the other of said relay devices is destroyed.
12. A telegraph receiving system for receiving one transmission of signals and a single subsequent repetition of the same signals, comprising in combination, a signal receiving relay, a signal impulse storage device comprising two sets of storage elements operatively connected to said 30 receiving relay and organized for one set to store the signal impulses of dot signals of the original transmission and the repetition and the other set to store the signal impulses of the dash signals of the original transmission and the repetition in separate storage elements and for different periods to bring the corresponding signals of the original transmission and of the repetition into step, means responsive to a pre-determined degree of distortion in the received signals and

operative upon said signal storage device to destroy the identity of signal impulses stored therein by storing dot and dash impulses simultaneously in the respective storage units, and a receiving apparatus comprising a pair of electromagnetic relays connected to receive simultaneously the stored signal impulses representing a dot signal of the original transmission and the same dot signal of the repetition, a further pair of electromagnetic relays connected to receive 10 simultaneously the stored signal impulses representing a dash signal of the original transmission and the same dash signal of the repetition, a receiving or recording circuit for the dot signals including the contacts of said first pair of relays 15 in series connection and a receiving or recording circuit for the dash signals including the contacts of said second pair of relays in series connection.

13. A telegraph receiving system for double-current cable code signals including three kinds 20 of signals consisting of only two current conditions persisting for different portions of a signal period, comprising in combination, a signal receiving relay responsive to the said two current conditions, synchronously-driven switching gear 25 connected to the contacts of said relay and timed to pass forward current impulses from one or other contact of said relay upon the reception of a signal of two of the said three kinds of signals, a signal impulse storage device comprising a set 30 of storage elements for storing the signals of one kind and a second set of storage elements for storing the signals of a second kind, means responsive to a pre-determined degree of distortion in the received signals and operative upon said 35 signal storage device to destroy the identity of signal impulses stored therein and a receiving apparatus connected to receive simultaneously the stored signal impulses representing a signal of the original transmission and the same signal 40 of the repetition and to be unaffected by stored signal impulses whose identity has been destroyed.

ALBERT HENRY MASSON.
